UNITED STATES PATENT OFFICE.

NAGAKATA NISHI AND NAGASUMI NISHI, OF BERKELEY, CALIFORNIA.

THERMAL CIRCUIT-CONTROLLER.

1,348,514.

specification of Letters Patent.

Patented Aug. 3, 1920.

Application filed January 11, 1919. Serial No. 270,728.

To all whom it may concern:

Be it known that we, NAGAKATA NISHI and NAGASUMI NISHI, subjects of the Emperor of Japan, residing at Berkeley, in the county of Alameda and State of California, have invented certain new and useful Improvements in Thermal Circuit-Controllers, of which the following is a specification.

10 Our invention is an automatically controlled electric iron, comprising means whereby the electric current may be automatically shut off when the heat of the iron rises to a predetermined degree and automatically turned on when the iron cools slightly below said degree.

15 In this specification and the annexed drawings, we disclose our invention in the form which we consider the best, but we do not limit our invention to such form because it may be embodied in other forms, and it is to be understood that in and by the claims following the description herein we intend to cover our invention in whatever form it 25 may be embodied.

Referring to the drawings:

Figure 1 is a vertical longitudinal section of our iron taken on line 1—1 of Fig. 4.

20 Fig. 2 is a rear elevation of the iron with the rear portion of the automatic control means removed to illustrate the invention more clearly.

Fig. 3 is a vertical longitudinal section of the iron taken on line 3—3 of Fig. 4.

25 Fig. 4 is a horizontal section of the iron taken on line 4—4 of Fig. 1.

Fig. 5 is a bottom plan view of the heating element.

30 Fig. 6 is a top plan of the heating element. Fig. 7 is a sectional view showing the coupling member 77 and the lower part of bar 70 and the screw securing said member to said bar.

35 Fig. 8 is a sectional view showing the coupling member 76, the upper end of stud 60 and plug 64 for mounting the member 76 on said stud.

40 Fig. 9 is a detail sectional view taken on an enlarged scale taken on line 9—9 of Fig. 2.

45 In the drawings, 1 indicates a base which is formed with a lower ironing surface 2. A pair of upstanding studs 3 and 4 are screwed into the top of base 1 on the central axis thereof. On top of the base 1 rests a plate of mica 5, the studs 3 and 4 extending

through apertures 6 and 7 in said plate. On the mica plate 5 rests a heating element 10 which includes a pair of flat heating coils 11 and 12 wound on mica plates 13 and 14, a 60 plate of mica 15 covering said heating coils, and a pair of metal conductor plates 16 and 17 resting on plate 15 directly over said heating coils; the studs 3 and 4 projecting through apertures 18 and 19 in plate 15 and 65 between the heating coils 12 and 13 and between the plates 16 and 17. The heating coils 12 and 13 and plates 16 and 17 are secured upon the plate 15 by rivets 20 and 21, the rivet 20 holding the heating coil 11 and 70 plate 16 to the plate 15, and the rivet 21 holding heating coil 13 and plate 17 to plate 15. A plate 23 of mica rests upon the plates 16 and 17 of the heating element 10, the studs 3 and 4 extending through apertures 75 24 and 25 in the plate. A thick metal plate 26 provided with apertures 27 and 28 rests upon the mica plate 23, the studs 2 and 3 extending through said apertures. Nuts 29 and 30 screw on the upper ends of the stud 80 bases against the top plate 26 and clamp the heating element 10 and mica plates 5 and 23 between the plate 26 and base 1. The upper portions of the studs 3 and 4 are reduced and threaded. A cover 35 provided 85 with apertures 36 and 37 fits upon the base 1 over the heating element 10 and plates 5, 23 and 26 and nuts 29 and 30, the reduced upper portions of studs 3 and 4 extending through said apertures 36 and 37. Nuts 38 90 and 39 screw on the reduced portions of studs 3 and 4 against the top of the cover 35 and clamp said cover in position on the base 1 and over the parts as described. A handle bracket 40 provided with apertures 95 41 and 42 rests upon nuts 38 and 39, the studs 3 and 4 projecting through said apertures, and nuts 43 and 44 screw on the ends of said studs against the bracket and clamp the bracket in position. A handle 45 is secured to the upper ends of bracket 40.

On the rear of the iron is mounted a thermostat 50 for controlling the current in the heating coils 11 and 12. Said thermostat includes a body 51, of porcelain or other suitable insulation, formed in two vertical members 52 and 53, the lower end of which body rests in a recess 54 in the rear part of the cover 35 and the forward member 52 of said body rests against the rear 105 member of bracket 40. The body 51 is incased within a casing 55, the forward wall 110

of which rests against said rear bracket member. A bolt 56 extends through the rear wall of casing 55, body members 53 and 52, front wall of said casing and 5 through the rear member of handle bracket 40, and a nut 57 screws on the forward end of said bolt against said bracket member whereby said casing and body 51 are held in position at the rear of the iron as de- 10 scribed and as shown in the drawing. Studs 60, 61 and 62 of copper or other suitable material of the proper coefficient of expansion, heat conductivity, melting point and specific heat are welded or otherwise secured 15 to the top of the base 1 at the rear thereof and project upwardly through apertures 58, 58' and 59 in the bottom of recess 54 into space 63 within the body 51. The studs 60, 61 and 62 are of different heights, the stud 20 60 being the least in height, the stud 61 next in height and the stud 62 the highest. A plug 64 of suitable insulation is fitted in the top of stud 60 and projects upwardly therefrom. A bar 70 of porcelain or other 25 suitable insulation located within space 63 in the body 51 is coupled by coupling 75 to the upper end of stud 60 which coupling includes two interlocking members 76 and 77 the member 76 being secured on the upper end of plug 64 and the member 77 being secured to the lower end of bar 70 by means 30 of screw 78. The members 76 and 77 are formed with interlocking lugs 79 and 80 which interlock to couple the lower end of bar 70 to the upper end of stud 60. The bar 70 is provided with a conduit 81 extending from the inner end of screw 78 to the upper end of the bar through which conduit extends a conductor 82 which engages 35 the screw 78 at its lower end and a screw 83 at its upper end which screws into the upper end of the conduit. A nut 84 screws on the upper end of screw 83 against the lower coil of a spring 85 and connects the lower 40 end of said spring to screw 83. The spring 85 fits in space 86 in body 51 and bears at its lower end against the top of bar 70 and at its upper end against a metal head 45 87 fixed in a socket 88 in said body.

50 A plug 89 of insulation is fitted in the top of stud 62 and a collar 90 is secured on the upper end of said plug which carries a platinum contact 91. A horizontal arm 92 of porcelain or other suitable material is 55 pivoted at 71 within the space 63 in the body 51 and has a platinum contact 93 on its lower edge at its swinging end adapted to engage contact 91. A screw 94 extends upwardly through contact 93 and the swing- 60 ing end of arm 92 and a nut 95 screws on the upper end of said screw against the lower end of a spring 96 which rests within a space 97 in the body 51, and connects said spring to said screw. The lower end 65 of said spring bears upon the swinging end

of arm 92 while its upper end bears against a metal head 98 mounted in a socket 99 in the body 51, thus forcing the swinging end of arm 92 downward and the contact 93 into contact with contact 91. A wire 100 connects to head 87 and a wire 101 connects to head 98, which wires lead through a space 102 in body 51 and are twisted together and lead through an opening 103 in the top of casing 55. The upper end of the rear mem- 70 ber of bracket 40 has a rear extension 104 which extends rearwardly at a slight downward inclination and then downward. The upper part of the extension 104 has an aperture 105 through which the twisted wires 80 100 and 101 extend. The wires 100 and 101 are clamped to the lower end of extension 104 on the inside thereof by a clamp 106 which comprises a clamp member 107 and a bolt 108 and nut 109, said bolt extending 85 through the lower end of extension 104 and between wires 100 and 101 and through an aperture in said clamp member and said nut screwing on the inner end of said bolt against said clamp member and drawing 90 said clamp member against said extension and against said wires. A spring 110 surrounds the wires 100 and 101 above the extension 104 and rests at its lower end upon said extension, said spring preventing bending 95 and breaking of the wires.

The stud 61 has an upstanding threaded extension 111 on which screws a threaded sleeve 112 which constitutes an adjustable control element for engaging and raising 100 arm 92 and breaking electrical circuit of the iron between contacts 91 and 93. The sleeve 112 has a conical upper end 113 for accurate engagement with the under side of arm 92. A stud 114 projects radially from 105 the lower end of sleeve 112 on which stud an indicator 115 telescopes. A plate 116 is secured by screws 117 to the rear wall of the cover 35 from the upper edge of which plate a dial 118 extends horizontally in a 110 rearward direction on the face of which dial at its outer edge is a scale 119 indicating degrees of heat. The plate 116 is provided with a horizontal slot 120 and the dial 118 is provided with an arcuate slot 115 121 concentric with the axis of the sleeve 112 through which slot extends the indicator 115 the point 125 of which rests over the scale 119.

Insulators 130 and 131 are secured respectively to the forward face of studs 60 and 62 by screws 132. Said insulators are provided with vertical grooves 133 and 134 through which respectively extend wires 135 and 136, the wire 135 being secured at 120 one end to member 76 and at its other end to an upstanding lug 137 on the rear end of plate 116 by screw 138, and the wire 136 being secured at one end to metal collar 90 and at its other end to upstanding lug 139 125 130

on the rear of plate 17 by screw 140. The rear end of coils 11 and 12 extend through the mica plate 15 and connect to plates 16 and 17 near lugs 137 and 139. The forward 5 end of the conductor of the coil 11 extends onto the forward end of plate 14 and winds thereon forming coil 12.

By swinging the indicator 115 over the scale 119 to the mark indicating the desired 10 degree of heat, the sleeve 112 is turned and moved up or down on the threaded extension or shank 111 and the thermostat 50 set to shut off the current when the heat of the coils 11 and 12 reaches said predetermined 15 degree. As the heat of the iron rises the studs 60, 61 and 62 expand upwardly until the predetermined degree is reached, whereupon the point of sleeve 112, engaging arm 92, swings said arm upwardly on 20 its pivot and disengages contacts 91 and 93 and breaks the circuit including heating coils 11 and 12. The iron then cools and the studs 60, 61 and 62 contract until the point of the sleeve 112 is lowered sufficiently 25 to enable the arm 92 to swing down under the influence of spring 96 to bring contacts 91 and 93 into contact to reestablish the circuit and heat the iron.

The relative heights of the studs 60, 61 30 and 62 effect a corresponding expansion and contraction thereof. This enables the studs to expand from zero up to the predetermined degree before the stud 61 can raise the sleeve 112 and cause arm 92 to swing 35 and break the circuit.

When the iron cools, after the current is shut off at a predetermined degree of heat, the stud 60, being the lowest in height, expands less than the studs 61 and 62 and 40 maintains the pivot 71 elevated, so that the end of arm 92 has a shorter distance than it would otherwise have, to swing down in order to bring the contacts 91 and 93 into contact and reestablish the circuit, thus enabling 45 the arm to swing and make contact, as soon as the stud 61 contracts sufficiently and disengages sleeve 112 from said arm, as soon as the stud 62 has contracted only slightly. This operation makes it unnecessary 50 for the studs 61 and 62 to contract to zero before reestablishing the circuit.

The relative lengths of the studs 61, 62 and 63 and the distances at which they are spaced apart are determined by careful 55 experiment, in order to give the arm 92 the proper movement.

Having described our invention, we claim:

1. In an electric iron, a thermostat including 60 three expansible and contractible studs of different lengths mounted on the base of the iron, a bar connected to the shortest stud but insulated therefrom, an arm pivoted on said bar, a contact on said 65 arm, a contact mounted on the longest stud,

but insulated therefrom, to be engaged by the contact on said arm, said contacts being connected in series in the iron circuit, means on the stud of intermediate length for engaging the arm to break contact between 70 said contacts when said intermediate stud has expanded under a predetermined degree of heat.

2. In an electric iron, a thermostat including three expansible and contractible studs 75 of different lengths mounted on the base of the iron, a bar connected to the shortest stud but insulated therefrom, an arm pivoted on said bar, a contact on said arm, a contact mounted on the longest stud, but 80 insulated therefrom to be engaged by the contact on said arm, said contacts being connected in series in the iron circuit, a threaded shank on the stud of intermediate length, a sleeve screwing on said shank 85 for engaging the arm to break contact between said contacts when said intermediate stud has expanded under a predetermined degree of heat, a dial, and an indicator on said sleeve for pointing to the degrees of 90 heat marked on said dial.

3. In an electric iron, a thermostat including three expansible and contractible studs of different lengths mounted on the base of the iron, a bar connected to the 95 shortest stud, an arm pivoted to said bar, a contact on said arm, a contact mounted on the longest stud, said contacts being included in the iron circuit, means on the stud of intermediate length for engaging 100 the arm to break contact between said contacts when said intermediate stud has expanded under a predetermined degree of heat, a spring bearing against the end of said bar, and a spring bearing against the 105 swinging end of said arm.

4. In an electric iron, a thermostat including three expansible and contractible studs of different lengths mounted on the base of the iron, and projecting through 110 the cover of said base, a bar detachably connected to the shortest stud and permitting removal and replacement of the cover on the base, an arm pivoted to said bar, a contact on said arm, a contact mounted on 115 the longest stud but insulated therefrom, said contacts being included in the iron circuit, means on the stud of intermediate length for engaging said arm to break contact between said contacts when said intermediate stud has expanded under a predetermined 120 degree of heat.

5. In an electric iron, a thermostat including two expansible and contractible studs mounted on the base of the iron, an 125 arm, means for mounting said arm on said base, a contact on said arm, a contact mounted on one of said studs with which the contact on the arm engages, said contacts being included in the iron circuit, and 130

- means on the other stud for engaging said arm and breaking said contacts when the studs have expanded under a predetermined degree of heat.
5. In an electric iron, a thermostat including an expansible and contractible stud mounted on the base of the iron, an arm, a contact on said arm, a contact to be engaged by said arm contact, said contacts being included in the iron circuit, a threaded member on said stud, and a sleeve screwing on said threaded member for engaging said arm and breaking said contacts when the stud has expanded under a predetermined degree of heat.
10. 6. In an electric iron, a thermostat including an expansible and contractible stud mounted on the base of the iron, an arm, a contact on said arm, a contact to be engaged by said arm contact, said contacts being included in the iron circuit, a threaded member on said stud, a sleeve screwing on said threaded member for engaging said arm and breaking said contacts when the stud has expanded under a predetermined degree of heat, an indicator on said sleeve, and a dial with heat graduations to which said indicator points to indicate the degree of heat at which said sleeve is set to engage said arm to break said contacts.
15. 7. In an electric iron, three expansible and contractible studs of different lengths mounted on the base of the iron, a cover for said base formed with a recess, one wall of which being open to receive said studs, a hollow insulating body resting in said recess over said studs, a bar connected to the shortest stud within said body, an arm pivoted to said bar, a contact on said bar, a contact mounted on the longest stud, said contacts being included in the iron circuit, means on the stud of intermediate length for engaging said arm to break said contacts when the iron has reached a predetermined degree of heat, and means for securing said on the iron.
20. 8. In an electric iron, three expansible and contractible studs mounted on the base of the iron, a cover for said base formed with a recess, one wall of which being open to receive said studs, a hollow insulating body resting in said recess, over said studs, a bar connected to the shortest stud within said body, an arm pivoted to said bar, a contact on said arm, a contact mounted on the longest stud, said contacts being included in the iron circuit, means on the stud of intermediate length for engaging said arm to break said contacts when said intermediate stud has expanded under a predetermined degree of heat, said body being formed in two sections, and a bolt extending through said sections and through the handle bracket of the iron and a nut on one end of said bolt for holding said body on the iron.
25. 9. In an electric iron, an expansible and contractible stud mounted on the base of the iron, a contact mounted on said stud, an arm, a contact on said arm for engaging said other contact to close the iron circuit, and means for automatically swinging said arm and breaking said contacts when the iron reaches a predetermined degree of heat.
30. 10. In an electric iron, a thermostat including an expansible and contractible stud, 65 mounted on the base of the iron, an arm, a contact on said arm, a contact engaged by said arm contact, said contacts being included in the iron circuit, a threaded member on said stud, and a sleeve screwing on 70 said threaded member for engaging said arm and breaking said contacts when the stud has expanded under a degree of heat determined by said sleeve and threaded stud member.
35. 11. In an electric iron, three studs mounted on the base of the iron, an arm pivotally mounted on one of said studs, a contact on one of the other studs, a contact on said arm for engaging the contact on 80 said stud, the third stud being expansible and contractible, and means on said expansible and contractible stud for engaging said arm and disengaging said contacts when said stud has expanded under a pre- 85 determined degree of heat.
40. 12. In an electric iron, three studs mounted on the base of the iron, an arm pivoted on one of said studs, a contact on another stud, a contact on said arm for en- 90 gaging the contact on said stud, the third stud being expansible and contractible, a threaded part on said expansible and contractible stud, and a threaded sleeve screwed on said threaded part of said expansible 95 and contractible stud for engaging said arm and breaking said contact under a predetermined degree of heat.
45. 13. In an electric iron, three studs mounted on the base of the iron, a detach- 100 able cover for said base through which said studs extend, an arm pivotally mounted on one of said studs, a contact on another stud, a contact on said arm for engaging the contact on said stud, the third stud being ex- 105 pansible and contractible, means on said expansible and contractible stud for engaging said arm and disengaging said contacts when the iron reaches a predetermined degree of heat, and a hollow insulated body 110 telescoped over said studs.
50. 14. In an electric iron, three studs mounted on the base of the iron, an arm pivotally mounted on one of said studs, a contact on said arm, a contact on another 115 stud engaged by said arm contact, a spring bearing upon said arm to maintain said contacts in engagement, the third stud being expansible and contractible, and means on said expansible and contractible stud for engaging said arm and disengaging said contacts when the iron reaches a predetermined degree of heat.
55. 120 In testimony whereof we affix our signatures.
